UNITED STATES PATENT OFFICE.

GEORGE H. MAAS, OF MILWAUKEE, WISCONSIN.

COVER-WRENCH FOR FRUIT-JARS.

1,157,632.

Specification of Letters Patent.

Patented Oct. 19, 1915.

Application filed April 1, 1912. Serial No. 687,904.

To all whom it may concern:

Be it known that I, GEORGE H. MAAS, a citizen of the United States, residing at Milwaukee, county of Milwaukee, and State 5 of Wisconsin, have invented new and useful Improvements in Cover-Wrenches for Fruit-Jars, of which the following is a specification.

My invention relates to improvements in 10 cover wrenches for fruit jars, and it pertains more especially, among other things, first, to the means for increasing the friction between the clamping wire of the wrench and the cover of the fruit jar, whereby the liability of the wrench slipping on the cover as the latter is being screwed on and off of the jar, is prevented, and second, to the modified form of operating handles with which the clamping wire is used.

20 My invention is further explained by reference to the accompanying drawings, in which—

Figure 1 is a front view, and Fig. 2 a side view of a preferred form thereof, and 25 Fig. 3 is a front view and Fig. 4 a side view of a modified form.

Like parts are identified by the same reference numerals throughout the several views.

30 It will be understood that the clamping wire 1 shown in the several views, is of ordinary construction, and that the same, when in use, is adapted to engage the periphery of a fruit jar cover as it is being used for screwing such cover on and off of the jar. To prevent the clamping wire from slipping upon the cover when thus used, I have provided the same with a fine spirally coiled wire 2, which coiled wire forms a gripping contact surface between the cover and clamping wire and prevents such wire from slipping upon the cover, as stated.

The form of operating handles 3, 3, shown in Figs. 1 and 2, are of ordinary construction, and the clamping wire is provided at its respective ends with hooks 4, 4, also of ordinary construction, which hooks are adapted to engage in the apertures 5 of the handles shown in said Figs. 1 and 2,

The handles 3 are pivotally connected together by a rivet 6 at a distance from their ends in the ordinary manner.

By the modified form of cover wrench shown in Figs. 3 and 4, the handles 7, 7 are pivotally connected together at their converging ends by a rivet 7', and the clamping wire 1 is connected with such handles at a distance in rear of said pivot by the hooks 4, which engage in the apertures 9.

In view of the fact that the front ends of the handles 7 are brought within the circle described by the clamping wire 1, as shown in Figs. 3 and 4, it becomes necessary to attach such wires to the handles upon one side of their longitudinal center so that the protruding front ends of such handles will be thereby brought above the upper surface of the cover, while the latter is being clamped by said wire. To accomplish this object the pivoted ends 8, 8 of said handles are formed upon one side of the handles proper 7, while the ends of the clamping wire 1 are connected with the apertures 9 upon the opposite sides of said handles, whereby, as the clamping wire is brought around the cover, the pivoted ends of said handles are brought above the upper surface of the cover, whereby the clamping wire may be caused to firmly impinge the periphery of the cover by bringing the handles 7 together.

Having thus described my invention, what I claim as new, and desire to secure by Letters Patent, is—

1. The combination with the clamping wire of a cover wrench, of a friction wire spirally wound upon the surface of said clamping wire, said spirally wound wire being adapted to form a friction bearing between the clamping wire and said cover.

2. In a cover wrench, the combination of a pair of handles pivotally connected together at one end, said handles being each provided at intermediate points between their pivotally connected ends and their opposite ends with perforations for the reception of the respective ends of a clamping

wire, a clamping wire having its respective ends inserted through the perforations of said handles respectively, said clamping wire being located on a different plane from the pivotally connected ends of said handles, and a spirally wound friction wire in-

In testimony whereof I affix my signature in the presence of two witnesses.

GEORGE H. MAAS.
